UNITED STATES PATENT OFFICE.

ROBERT KLIPFEL, OF LARIMORE, NORTH DAKOTA.

PENCIL-HOLDER AND POINT-PROTECTOR.

No. 854,507.

Specification of Letters Patent.

Patented May 21, 1907.

Application filed August 7, 1906. Serial No. 329,538.

To all whom it may concern:

Be it known that I, ROBERT KLIPFEL, a citizen of the United States, and a resident of Larimore, in the county of Grand Forks and 5 State of North Dakota, have invented a new and Improved Pencil Holder and Point Protector, of which the following is a full, clear, and exact description.

This invention relates to certain improvements in devices for holding pencils and protecting the points thereof when the pencils are not in use, and provided with a fastener by which the same may be instantly secured to the inside or outside of a pocket or to any 15 other portion of the clothing.

Reference is to be had to the accompanying drawings forming a part of this specification, in which similar characters of reference indicate corresponding parts in all the 20 figures, in which

Figure 1 is a side elevation of my improved pencil holder and point protector; Fig. 2 is a vertical section on the line 2—2 of Fig. 1, showing the pencil in place; Fig. 3 is a vertical section at right angles to the section shown in Fig. 2, and showing the pencil removed; and Fig. 4 is a side elevation of a portion of the holder, showing the fastener for securing the same to the clothing.

My improved holder comprises a tube 1 adapted to receive the pencil 2 and of a length slightly less than the depth of an ordinary vest pocket. This tube is slightly larger in cross section than an ordinary pencil and is substantially closed at the bottom and provided with a slightly flaring opening 3 at the top. Adjacent the upper end of the tube is provided a spring 4, having one end thereof secured in any suitable manner to the 25 wall of the tube, and having a portion 5 thereof extending through a slot in the wall of the tube, adapted to press against the pencil within the tube. The end 6 of this spring is bent away from the tube, whereby the finger nail may be inserted beneath the end and withdraw the spring from the slot in case a very short pencil is carried in the holder and the outer end of said pencil is too far within the tube to permit of its being withdrawn 45 by taking hold of the end.

Within the tube 1 is a point protector 7, substantially funnel shaped and having its larger end of a diameter substantially equal to the inner diameter of the tube. The 55 lower end 8 of the point protector is preferably formed slightly larger than the diameter

of the lead of the pencil and is preferably cylindrical; so that the pointed lead may extend downward within said cylindrical portion and thus be prevented from coming in contact with any portion of the holder or 60 protector.

Within the tube and beneath the point protector is a coil spring 9, adapted to force the protector to the upper end of the tube, thereby keeping it in contact with the end of the pencil at all times, irrespective of how short the pencil may be or how far it is inserted within the holder, while in order to protect the spring 9 against injury by being crowded together at the bottom of the tube 1 from the pencil being pushed down too far, the cylindrical part 8 of the point protector 7 should be sufficiently long to serve as a stop.

For preventing the removal of the spring 75 and protector, the upper end of the tube is provided with an annular inwardly-directed projection 10, acting as a stop, and against which the protector is pressed when the pencil is removed. The top edge of this stop 10 80 should be rounded off toward the wall of the tube 1, so that if the pencil is carelessly inserted in the holder and the point thereof pushed down the side of the tube, it will be protected against injury, by being guided 85 into the point protector 7.

The operation of the holder and protector is very simple, as all that is necessary is to insert the pencil within the upper end of the tube and press it inward any suitable or desired distance. The protector is always in contact with the sharpened end of the pencil and the pencil is held in place by the spring 4, which presses against the side thereof with sufficient force to prevent the accidental removal of the pencil, but not with sufficient force to prevent the pencil from being easily inserted or pulled out. By means of the movable point protector and the coiled spring a short pencil cannot fall to the bottom of the tube but is held in any desired position just as securely as is a much longer pencil. The 95 protector prevents the pencil from moving from side to side or in any other way, having the point thereof broken off.

For securing the improved pencil holder above described to a garment, it is provided with a clamp or fastener 11, preferably in the form of a flat piece of metal 12 bent to form upper and lower jaws, which will allow the garment to be slipped in between them. For holding the jaws in place and operating them 100 105 110

there is provided a second U-shaped piece of metal 13 inclosing the jaws 12 and provided with a lever 14. These jaws are preferably provided with teeth 15 for more securely holding the material inserted between them.

The upper end of the tube 1 is provided with a flat metal plate 16 secured thereto in any suitable manner, and to this plate 16 is pivotally mounted the fastener 11 above described. The two are held together by a suitable rivet 17, while the fastener is provided with a small projection or pin 18, adapted to enter a recess in the face of the plate 16 and hold the fastener in alignment with the tube. The fastener being composed of spring metal, it may be turned on the pivot 17, and by providing a plurality of recesses in the face-plate 16, the fastener and tube may be held in any desired relationship. By thus pivotally mounting the tube on the fastener, the latter may be secured to the horizontal edge of a pocket or to the vertical edge of a suspender, or any other desired location, and the tube will be prevented from swaying with every movement of the body. The movement of the fastener in respect to the tube is clearly indicated in Fig. 4, where the fastener is shown in two different positions.

It will be noted that in my improved pencil holder and point protector above described, the pencil is supported at two places, namely, at the open end of the tube and at the sharpened end of the pencil, but the pointed lead at no time comes in contact with any portion of the holder or protector. This double support for the pencil is present irrespective of the length of the pencil, as the very shortest may be held as well as the very longest.

The holder may be secured at any desired angle by the relative rotation of the holder and fastener and when in any desired position it is firmly held against accidental displacement by the projection 18.

Having thus described my invention, I claim as new and desire to secure by Letters Patent:

1. A pencil holder and point protector,

comprising an open-ended tube, a funnel-shaped point protector slideable within said tube and having an outwardly-extending flange in engagement with the walls of said tube, a spring beneath said point protector and in engagement with the bottom of the tube and with said flange and normally pressing the protector toward the open end of the tube, and means within the tube for preventing the removal of the protector from the tube.

2. A pencil holder and point protector, comprising an open-ended tube, means adjacent the open end of the tube for holding a pencil within the same, a funnel-shaped point protector movable within the tube and terminating in a cylindrical portion adapted to receive the lead of the pencil, a coil spring beneath the point protector and normally pressing it toward the open end of the tube, and means adjacent the open end of the tube for preventing the displacement of the point protector.

3. A pencil holder, comprising an open ended tube, means at the upper end of said tube for holding a pencil in position, a funnel-shaped point protector slideable within said tube, a spring beneath said point protector normally pressing it toward the open end of the tube, and a fastener for securing the tube to any desired support.

4. A pencil holder and point protector, comprising an open ended tube, means within said tube for holding a pencil within the same, a point protector movable within said tube, a face plate secured to said tube adjacent its open end, a fastener pivotally secured to said face plate, and a projection on said fastener adapted to enter a recess in the face plate and hold the fastener and face plate against free relative movement.

In testimony whereof I have signed my name to this specification in the presence of two subscribing witnesses.

ROBERT KLIPFEL.
